UNITED STATES PATENT OFFICE.

NICHOLAS MAINZ AND GEORGE J. ZELLER, OF WASHINGTON HEIGHTS,
ILLINOIS.

HEATING-DRUM.

SPECIFICATION forming part of Letters Patent No. 621,115, dated March 14, 1899.

Application filed April 9, 1898. Serial No. 677,022. (No model.)

To all whom it may concern:

Be it known that we, NICHOLAS MAINZ and GEORGE J. ZELLER, citizens of the United States, residing at Washington Heights, in

5 the county of Cook and State of Illinois, have invented certain new and useful Improvements in Heating-Drums; and we do hereby declare the following to be a full, clear, and exact description of the invention, such as
10 will enable others skilled in the art to which it appertains to make and use the same.

This invention relates to heating-drums; and it consists in the novel construction and combination of the parts hereinafter fully described and claimed.

15 In the drawings, Figure 1 is a vertical section through the heating-drum. Fig. 2 is a sectional plan view taken on the line $\alpha\alpha$ in Fig. 1.

20 A is the outer casing or shell of the heating-drum.

B is the bottom plate, and C is the top plate. The top and bottom plates are secured to the shell in any approved manner. The shell is 25 shown of circular form; but it may be of any other approved form, such as rectangular or oval, and it and the top and bottom plates may be made of wrought iron, cast-iron, or any other approved material which is a good 30 conductor of heat.

D are vertical heating-tubes which pass through the chamber of the heating-drum and have their end portions secured to the top and bottom plates in any approved manner.

35 E is an inlet-pipe for the products of combustion or hot air from any approved form of heater, radiator, or furnace. The inlet-pipe is connected to the bottom plate in any approved manner, said bottom plate being 40 preferably provided with a collar e for the inlet-pipe to engage with.

F is an outlet-pipe connected to the top plate in any approved manner, said top plate being preferably provided with a collar f for 45 the outlet-pipe to engage with.

F' is a removable portion of the outlet-pipe or extension-pipe, which depends within the heating-drum between the heating-tubes and which has its lower open end arranged over 50 and in proximity to the open end of the inlet-

pipe. The pipe F' may be a mere extension or prolongation of the pipe F; but it is preferably a separate extension-pipe connected to the outlet-pipe proper.

The pipe F' is arranged inside the collar f 55 and is provided with a projecting bead f' for supporting it, and the outlet-pipe F is slipped over the upper end portion of the pipe F' and the collar f . The distance between the inlet and outlet pipes can be adjusted, if desired, 60 either by sliding the pipe F' upward inside the pipe F or by removing the pipe F' and inserting a similar pipe of a different length in place of it.

G is a partition which is connected to the 65 bottom plate B on one side of the inlet-pipe. This partition extends between the inlet and outlet pipes diagonally and thence upward, leaving an opening or space g in the upper part of the heating-drum above the bottom 70 of the outlet-pipe. The partition G is provided with an opening g' between the mouths of the inlet and outlet-pipes, and H is a damper for closing the said opening. Any approved form of damper may be used.

75 The partition G has a vertical side portion 2 on one side of the pipe F' , a front portion 3, and a back portion 4. The front and back portions are each arranged at an obtuse angle to the side portion 2, and they are provided with flanges 5, by which they are connected to the shell A on the opposite side of the pipe F' from the side portion 2. The inclined portion 6 of the partition is attached to the bottom edges of the parts 2, 3, and 4, 80 and it is provided with a flange 7 at its lower part, by which it is attached to the bottom plate B of the drum on the opposite side of the inlet-pipe from the part 2.

85 The damper H is preferably a slidable plate, 90 and h are guides for the damper-plate. A rod h' is provided as a means for sliding the damper-plate back and forth and is carried through a hole in the shell. The partition can be made in several parts, if desired, and 95 of any approved material or materials, and it is preferably shaped and constructed so as to partially encircle the outlet-pipe and leave room for as many heating-tubes as possible. When the damper is closed, the heat passes 100

into the upper part of the drum and over the top of the partition, being brought in contact with all the tubes, and passes downward and into the open end of the outlet-pipe. When 5 the damper is opened, the heat in a great measure passes direct from the inlet-pipe to the outlet-pipe and the heating effect of the drum is reduced. It will be noticed that the draft through the heating-drum is never cut 10 off or obstructed.

What we claim is—

In a heating-drum, the combination, with a casing, an inlet-pipe connected to its bottom plate, and an outlet-pipe connected to its top 15 plate and depending within the casing over the inlet-pipe; of a partition comprising side, front, back and inclined portions, 2, 3, 4 and 6, said side portion being arranged on one side of the outlet-pipe, and the said front and back

portions being arranged at an obtuse angle to 20 it and connected to the casing on the other side of the inlet-pipe, and the said inclined portion having an opening g' and extending from the bottom edges of the parts 2, 3 and 4 diagonally between the said inlet and outlet pipes and 25 having its lower part connected to the bottom plate of the said casing, a space g being left between the top of the partition and the top plate of the said casing, and a damper for regulating the passage through the opening g' , 30 substantially as set forth.

In testimony whereof we affix our signatures in presence of two witnesses.

NICHOLAS MAINZ.
GEORGE J. ZELLER.
